UNITED STATES PATENT OFFICE.

HOWARD POPE, OF HOLLIDAYSBURG, PENNSYLVANIA.

EAVES-TROUGH HANGER.

SPECIFICATION forming part of Letters Patent No. 707,941, dated August 26, 1902.

Application filed March 15, 1902. Serial No. 98,876. (No model.)

To all whom it may concern:

Be it known that I, HOWARD POPE, a citizen of the United States, residing at Hollidaysburg, in the county of Blair and State of Pennsylvania, have invented a new and useful Eaves-Trough Hanger, of which the following is a specification.

This invention relates generally to eaves-trough or gutter hangers, the object of the invention being to provide a simple and efficient construction of hanger which can be quickly and easily adjusted to suit various conditions, whereby the gutter may be held at the proper position below the eaves of the roof.

With this object in view the invention consists, essentially, in constructing a hanger and bracket members in such a manner that they can be quickly and easily connected to each other and also quickly and easily adjusted with reference to each other.

The invention consists also in certain details of construction and novelties of combination, all of which will be fully described hereinafter and pointed out in the claims.

In the drawings forming part of this specification, Figure 1 is a perspective view showing the practical application of my invention. Fig. 2 is a side elevation of a device illustrating my invention. Fig. 3 is a detail perspective view showing inner face of the lower portion of the hanger member. Fig. 4 is a detail perspective view of the bracket member. Fig. 5 is a sectional view on the line 55 of Fig. 2. Figs. 6, 7, and 8 are views illustrating a slightly-modified means for securing the hanger member.

In carrying out my invention I employ a hanger member A, the upper portion of which is adapted to be secured to the lower end of the roof, the lower end depending vertically from the edge of the roof, and said depending portion is slotted vertically, as shown at A', and the rear face of the said depending portion is provided with serrated ribs A² on opposite sides of the slot A'.

The hanger member B comprises the curved supporting-arm B' and the plate or bearing portion B², which is preferably formed integral with the supporting-arm B' and is adapted to bear against the depending member of the hanger. This plate B² has a rear-

wardly-extending lug B³, which is adapted to pass through the slot A', and adjacent to the upper end of the plate is a T-shaped pin B⁴, 55 which is adapted to pass through the slot and engage the notched ribs at the rear of the depending portion of the hanger. The lug B³ has an opening B⁵ produced therein, through which a locking-pin B⁶ is passed, said pin 60 also engaging the notched ribs A² adjacent to their lower ends, the T-shaped pin B⁴ engaging them adjacent to their upper ends, as most clearly shown in Fig. 2, and by this construction the bracket-arm B is securely fastened to the hanger member. The bracket-arm is also provided with a forwardly-projecting lip B⁷, which is adapted to grasp the inner edge of the gutter, as most clearly shown in Fig. 1.

In Fig. 6 I have shown a circular plate A⁴, which is adapted to be secured to the side of the building, said plate having the tapering guides A⁵ connected thereto, in which fit the wedge-shaped wings A³, carried by the depending hanger member, as most clearly shown in Fig. 7, and it will be understood that this construction is employed in cases where it is not convenient to attach the hanger member to the roof of the building. 75 The other portions of the device, however, are identical with those already described, and the operations will of course be the same.

By means of the hanger member and supporting-brackets constructed as herein shown 85 and described I am enabled to quickly and easily adjust the supporting-bracket upon the hanger member, so that the gutter can be held at the proper position beneath the eaves of the building.

Having thus fully described my invention, what I claim as new, and desire to secure by Letters Patent, is—

1. A device of the kind described comprising the hanger member having a depending 95 vertical slotted portion, the inner face of which is provided with notched ribs, and a bracket-arm having a T-shaped pin, and a perforated lug adapted to be passed through the said slotted member, and a pin adapted 100 to be passed through the said perforated lug, and engage the notched ribs, substantially as specified.

2. The combination with the hanger mem-

ber, the depending portion of which is slotted vertically and provided with notched ribs upon opposite sides of the said slot, of a bracket-arm having a T-shaped pin adjacent 5 to its upper end and a perforated lug adjacent to its lower end, said lug being adapted to be passed through the vertical slot, and a locking-pin adapted to be passed through the perforated lug, for the purpose described.

10 3. The combination with a hanger member having its depending portion slotted vertically and provided with notched ribs upon opposite sides of the slot, the bracket member comprising the curved supporting-arm 15 having the forwardly-projecting lip, and the plate having the T-shaped pin at its upper end, and a rearwardly-projecting perforated lug adjacent to its lower end, and the lock-

ing-pin adapted to be passed through the said perforated lug for the purpose specified. 20

4. The combination with the plate having the tapering guides, of a hanger member having tapering wings adapted to fit said tapering guides, said member being slotted vertically and provided with notched ribs on opposite sides of the slot, and the bracket member having rearwardly-projecting T-shaped pin adjacent to its upper end, and a perforated lug adjacent to its lower end, and the locking-pin adapted to be passed through 25 30 said perforated lug for the purpose specified.

HOWARD POPE.
